UNITED STATES PATENT OFFICE

163,474

COMBINED HEDGE TRIMMER AND LAWN
EDGER

Neil C. Norton, San Dimas, Calif.

Application November 17, 1950, Serial No. 13,028

Term of patent 14 years

(Cl. D22—4)

To all whom it may concern:

Be it known that I, Neil C. Norton, a citizen of the United States of America, residing at San Dimas, in the county of Los Angeles, and State of California, have invented a new, original, and ornamental Design for a Combined Hedge Trimmer and Lawn Edger, of which the following is a specification, reference being had to the accompanying drawing, forming a part thereof.

In the drawings:

Figure 1 is a perspective view of a combined hedge trimmer and lawn edger showing my new design;

Figure 2 is a plan view on an enlarged scale thereof taken on line 2—2 of Fig. 1.

The dominant features of the design reside in the portions shown in full lines.

I claim:

The ornamental design for a combined hedge trimmer and lawn edger, as shown, and described.

NEIL C. NORTON.
